UNITED STATES PATENT OFFICE.

CHARLES H. STRATTON, OF SALEM, OHIO.

WAGON JUMP-SEAT.

SPECIFICATION forming part of Letters Patent No. 299,437, dated May 27, 1884.

Application filed November 8, 1883. (No model.)

To all whom it may concern:

Be it known that I, CHARLES H. STRATTON, a citizen of the United States of America, residing at Salem, in the county of Columbiana and State of Ohio, have invented certain new and useful Improvements in Jump-Seats; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to jump-seats so constructed and arranged that one seat can be moved backward, under, and forward from under another, which is simultaneously moved backward and forward automatically—that is, 20 as one seat which is folded under another is moved forward and erected, the other is, by intermediate mechanism, moved backward, and vice versa.

The invention consists in certain novel constructions and combination of devices by 25 which the relative movements of the seats are effected, and the two seats supported in their different positions, as will be hereinafter particularly described with reference to the accompanying drawings, in which—

30 Figure 1 is a vertical longitudinal section through the center of the body of a vehicle provided with jump-seats according to my invention, one seat being arranged for use and the other folded back under it. Fig. 2 is a similar view showing the seats both arranged for use, one being shifted backward and the other raised and jumped forward. Fig. 3 is a detached top view of the locking-arms. Fig. 4 35 is a top view of the front seat with its supporting-bars shown in dotted lines. Fig. 5 is a perspective view of one of the base or rocker plates, and a portion of the back seat and its connections.

40 The letter A indicates the body of the vehicle; B, the sills; C, the front seat, and J the back seat. R is a base or rocker plate shown secured to the inner side of the sill B; and it will be understood that a similar plate is secured to the opposite sill, which plate, if desired, may be made in one or more pieces.

From the upper edge of the rear portion of the base-plate R, a lug or standard, r^2 , is bent outward from the top of the base-plate across the top of the sill, and then projects upward 55 from the outer edge of said sill. From the upper edge of the base-plate a lug, r^3 , is bent across the top of the sill and turned up slightly at its outer end.

The back seat, J, which may be constructed 60 in any suitable manner, has secured thereto, under each end, a block, I, recessed, as shown, at its front end, and to the inner side of this block is secured a plate, I', the front portion of which is bent into the recess in the end of 65 the block and then again forwardly, while its rear portion is connected to a leg, L, which is bent at l to form a shoulder under the block.

To the rear end of the plate I' is pivoted 70 one end of a lever, N, which is pivoted at the top of the standard r^3 , and has a short arm extending below its pivot. To the front end of the plate I' is pivoted one end of a link, N', the lower end of which is pivoted to the top 75 of the standard r^3 , which projects from the outer edge of the sill. The front seat, C, is supported at each end on a horizontal bar—such as shown at K—and the ends of this bar are pivoted to the upper ends of arms F F, the lower ends of which are pivoted to the 80 base-plate R on the inside of the sill, as will be seen clearly in the top view of the front seat in Fig. 4. The bar K, near its ends, has two inwardly-projecting bends or lugs, k k, through which pass the bolts which hold the 85 seat to the bar.

To the rear arm F on its inner side, is pivoted a bell-crank coupling-lever, S, with arms of different lengths, the short arm being turned downward, as shown in Figs. 1 and 2 90 in full lines. To this short arm is pivoted one end of a link, E', the other end of which is pivoted to an intermediate portion of a locking-lever, E, the front end of which is pivoted to the front arm F. The rear end of this 95 locking-lever laps the link E', and has a laterally-projecting toe, e, which extends across the upper edge of said link. Said locking-lever has also an inwardly-projecting U-shaped bend, e', in which is arranged a pin, to which 100 is pivoted one end of a brace-rod, E², the other end of which is pivoted similarly to the op-

posite locking-bar, as shown in dotted lines in Fig. 4. The long arm of the coupling-lever S is connected to the short arm of lever N under the back seat by a connecting-bar, D, the front portion of which is bowed upwardly to reach over the lever S, and is indented, as shown at d, so as to pass freely a pin, p, which projects inwardly from the rear arm F of the front seat. This pin p is intended to rest 10 nearly upon the upper edge of the connecting-bar D, so as to hold the connecting-bar D from raising and turning the link S and uncoupling it when the seat C is being pulled out from under seat J. So both seats take their position, as shown in Fig. 2, simultaneously, as is explained further on.

The operation of the jump-seats as now described is as follows, it being of course understood that both sides of the body are equipped with similar seat operating and supporting mechanisms: When the parts are in the positions shown in Fig. 1, the seat J only is arranged for immediate use, its leg L resting firmly upon the portion of the lug r², which is bent across the top of the sill, while the long arm of the lever N serves as a brace to prevent the seat from swinging either forward or backward. It will be readily understood that this leg L need not be used when 30 there is a frame at or near top of body for the seat to rest upon. The seat C may be folded back under seat J and out of the way, and its weight pressing against bar D, which is coupled to the short arm of lever N, holds the seat J in place, as shown in Fig. 1. When it is desired to use both seats, the seat C is grasped at any convenient point and pulled forward and upward until the arms F F stand vertically, or nearly so, as shown in Fig. 2. As these arms 40 rise the connecting-bar D pulls forward the short arm of lever N, and consequently the seat J is lifted and carried rearward, descending again when the lever N passes the center or vertical position, so that the leg L rests upon the lug r², which is bent across the top of the sill. The two lugs r¹ and r² thus serve as rests for the leg, in addition to the function of the lug r³ as a standard for pivotal connection with link N'. As soon as the arms F F 45 reach the upright position, the locking-lever E is to be pressed downward, so that its toe e rests upon the upper edge of link E', the locking-lever and link being thus brought in line and acting as a brace for the arms F F as the 50 coupling-lever S is prevented from turning by the connecting-bar D. By following the connections from the foot of the leg L it will be readily seen that as long as the locking-bar E and link E' remain in line both of the seats will be 55 maintained in the positions shown in Fig. 2. Now, if it is desired to throw the seat C forward and lower it for a child's seat, or to allow the back seat to be easily reached, as shown in dotted lines in Fig. 2, the locking-lever E 60 must be forced upward to break the lock, and

the arms F F being then swung forward and downward, the coupling-lever S will turn on its pivot, its long arm rising with the front end of the connecting-bar D, the bend d of which allows it to pass the pin p. The short 70 arm of lever S rises at the same time, and the descending arms F F carry down the locking-lever E and link E' until they again come in line with the toe e, resting upon the upper edge of the link, thus forming a support upon which the rearward lug, k, of the bar K rests, while the arms F F serve as braces. 75

If, instead of throwing the front seat forward from its upright position, it should be 80 desired to fold it back and bring the back seat forward to the middle of the body, the first step would be the same as before—that is, the lock would be broken by forcing the locking-arm upward, and then forcing the 85 front seat rearward until the pin p strikes the upper edge of the connecting-bar, the parts being thus in the positions shown in Fig. 1.

Having now fully described my invention and explained the operation thereof, I claim— 90

1. The combination, with the base or rocker plate adapted for attachment to the sill, and provided with the leg-rests, of the swinging back seat having a leg, L, the front seat, and connecting mechanism, whereby when 95 the front seat is shifted the back seat will be also shifted, and its leg changed from one rest to the other, substantially as described.

2. The combination, with the front and back seats, of the lever N and link N', pivoted at their upper ends to the back seat and below to permanent supports, the arms F F, pivotally connected with the front seat at the top and to permanent supports at their lower ends, the coupling-lever S, pivoted to the 105 rear arm F, the link E', and locking-arm E, connecting the short arm of the coupling-lever with front arm F, and the connecting-bar D, connecting the long arm of the coupling-lever with the short arm of the operating-lever N of the back seat, substantially 110 as described.

3. The combination, with the front and back seats, lever N, link N', and arms F F, of the coupling-lever S, link E', locking-lever 115 E, provided with toe e, the pin p, projecting from rear arm F, and the connecting-bar D, bowed upward at its front portion and having the indentation s, all connected and arranged for operation substantially as described. 120

4. The front-seat supporting-bar K, having the bends k k, substantially as described, and for the purpose set forth.

In testimony whereof I affix my signature in 125 presence of two witnesses.

CHARLES H. STRATTON.
